UNITED STATES PATENT OFFICE

SHELIDA P. STARK, OF OTTOSEN, IOWA

BOX-CAR-DOOR OPENER

Application filed September 24, 1928. Serial No. 308,112.

The present invention relates to car door structures, and more particularly to an opening and closing device for attachment to box cars and their doors.

An object of the present invention is to provide a device which may be quickly and easily attached to a box car or the like and to the door thereof for opening or closing the door, according to the adjustment of the device, the device being operable by a crank or the like which is adapted to increase the leverage of the opening or closing pressure on the door, and overcome the resistance of the door to sliding incident to the sagging of the door, pressure of material thereagainst or other causes.

It is well known that the sliding doors of box cars, such as when loaded with grain or the like, become practically impossible as to opening and closing, owing primarily to the sagging of the car body and to the warping, disalignment and sagging of the hanger track for the doors and their guide rails, and also incident to the swelling, binding and internal pressure against the doors. The present invention aims to provide a device which will exert sufficient pressure to operate the door under these adverse conditions, and which so applies the pressure between the body of the box car and the door as to not injure the same.

Another object of the invention is to provide a door opening and closing device of this character, which may be quickly and easily removed from a box car and its door and folded into compact form for easy transportation and storage in a relatively small space, and a device which may be quickly and easily opened and set up in position for use.

A still further object of the invention is to provide certain improvements over the construction set forth in my co-pending application Serial No. 120,371, filed July 3, 1926, and wherein the present invention is of simpler construction and of a reduced number of parts, and wherein the construction is relatively economical to manufacture and assemble.

In the drawings, wherein like symbols refer to like or corresponding parts throughout the several views,

Figure 1 is a fragmentary side elevation of a box car with its door in closed position, and with the improved device applied thereto.

Figure 2 is an enlarged edge view showing the operative portion of the invention on an enlarged scale and as applied to a portion of the box car.

Figure 3 is a horizontal section taken through the side of the box car substantially on the line 3—3 of Fig. 1 and looking in the direction of the arrows.

Figure 4 is a view similar to Figure 1 but with the door of the box car open and with the device of this invention adjusted accordingly.

Figure 5 is an enlarged horizontal section taken through the door post of the box car showing the operative device applied thereto, the section being taken substantially on the line 5—5 of Figure 2, and

Figure 6 is a horizontal section taken through the car door, showing the clamp of the present invention applied thereto.

Referring now to the drawings for a more particular description of the invention, and in which like or corresponding numerals refer to similar or like parts throughout the several views, 10 designates a box car of conventional form, which is provided with the usual sliding door 11 suspended by hangers 12 from a hanger rail or track 13 which is secured to the side of the box car 10 across the top of the door opening 14 and which extends considerably to one side thereof as shown in Figures 1 and 4.

The door 11 may be of any suitable construction and is shown as provided with longitudinal braces 15 for reinforcing the door.

The door is also provided with the usual hasp 16 adapted to engage a staple 17 which projects outwardly from a door post 18, which is located at the outer side of the door opening 14 and against which the forward edge of the door 11 is adapted to abut. The hasp 16 is held on staple 17 by a pin 19 or the like suitably carried by the box car body 10 for holding the door 11 closed. The body of the box car 10 is provided near one end with step rails 20 in the usual manner, and which are utilized

in the present instance for supporting certain parts of the present invention.

The invention primarily embodies three parts, an operating part, a clamp for the door, and a connection between the clamp and the operating part. The operating part comprises a frame 21, which may be in the form of a flap bar of suitable length and having its opposite ends overturned in spaced relation to provide brackets 22 and 23 through the lower one of which is mounted to turn a shaft 24 having a handle 25, the shaft 24 having in the bracket 23 a drum 26 upon which is wound one end of a cable 27.

15 The frame 21 is of any suitable length and is adapted to be disposed vertically against the post 18, the frame 21 having one or more openings or slots through which the staples 17 may project, so that the pin 19 when engaged in the staples may be utilized for holding the frame 21 firmly in position. At one or more points the frame 21 is provided with an over-turned flange 28 which, as shown in Figure 5, carries a binding screw 29 threaded through the flange and adapted to abut against the edge of the post 18 for securing the frame 21 rigidly in place. The frame 21 is positioned with the pulley 30, carried in the upper bracket 22 uppermost 30 and with the axis of the drum 26 and the pulley 30 transversely of the door. The cable 27 extends upwardly from the drum 26, over the pulley 30 and inwardly across the door opening 14. When the device is adjusted for 35 opening the door 11, the cable 27 is provided with a hook 31 adapted to engage in one of the step rails 20, and which carries a pulley 32 over which the cable 27 passes so as to change the direction of pull of the cable 27.

40 The free end of the cable 27 is provided with a detachable coupling 33 which may be in the form of a hook, as shown and which is adjustably connected to the door clamp, shown best in Figure 6.

45 The door clamp comprises a pair of rods 34, which are similar in construction, each rod having at its inner end an over-turned combined guide and stop flange 35, which is apertured for slidably receiving therethrough 50 the intermediate portion of the opposite rod 34, the rods being crossed or overlapped and interconnected through the flanges 35, so as to slide one upon the other.

The outer end of each rod 34 has a laterally 55 turned jaw 36 arranged to engage and preferably bite into the front and rear edges of the door 11, so as to hold the clamp in place, an expanding coil spring 37 being mounted upon the overlapping portions of the rods 34 60 between the flanges 35 to force the latter away from each other and thus draw the rods 34 into further overlapping engagement and bind the jaws 36 against the door. Each rod 34 is provided with an apertured eye 38 with 65 which is selectively connected the coupling

33. In which instance of use the coupling 33 is attached to the remote eye 38, so as to draw the remote jaw 36 against the door 11, so that the spring 37 serves merely to yieldingly hold the jaws 36 in binding relation against the door.

In use, when it is desired to open the car door 11 from the closed position shown in Figure 1, the frame 21 is fitted to the post 18, the hook 31 is connected to one of the step rails 20 with the cable 27 extending across the door 11 and along the side of the car 10 and returned over the pulley 32 and connected to the forward rod 34. The handle 25 is now turned so as to wind the cable 27 on the drum 26 with the result that increased leverage is provided over the pulley 32 and the leverage is also increased through the drum 26 and handle 25. The result of such a construction and arrangement is that considerable pressure is exerted on the door 11 to slide it into open position. When the door 11 is open, as shown in Figure 4, the hook 31 and pulley 32 are not used but may be supported in idle position, as shown in Figure 4, out of the way. The coupling 33 is connected to the rear rod 34 of the door clamp and the handle 25 operated as before.

This operation gives an increased leverage through the drum and handle and draws the door 11 across the opening 14 into closed position. The device may be quickly and easily applied to the car, and as easily and quickly removed therefrom after use. It is apparent that the adjustment of the device from the position shown in Figure 1 to that shown in Figure 4 may be very quickly and easily accomplished by merely disengaging the hook 31 from the step rail 20.

The device thus comprises but relatively few parts and the parts are of such construction that they may be economically manufactured and assembled, and the device when removed from the car may be folded into relatively small space for carrying about and for storage.

I do not wish to be restricted to the size, form, and proportions of the various parts, and obviously changes could be made in the construction herein described without departing from the spirit of the invention, it being only necessary that such changes fall within the scope of the appended claims.

What is claimed is:—

1. A door opening and closing device comprising an operating member, means for detachably connecting the operating member to a door post, a clamping member for engagement with the door, and adjustable connections between the operating member and the clamping member for operation across the door to move the same into open and closed positions.

2. A door opening and closing device comprising an operating member, means for de-

tachably securing the member to a door post, a clamp for engagement with the door, a connection between the clamp and the operating member, and an adjustable device carried by the connection for attachment to the door support for determining the direction of movement of the door.

5 3. A door opening and closing device for attachment to a box car having the usual door post, door hasp receiving staple and locking pin and the usual step rails, a frame for engagement against the door post and having an opening for receiving said staple to secure the frame to the post by said locking pin, a drum on the frame, a cable on the drum, a clamp adapted for attachment to the door, and a combined pulley and hook mounted on the cable adapted for connection with one of said step rails for stretching said cable 10 across said door and the side of the box car whereby to operate said door in a direction away from said frame upon the turning of said drum.

4. A door opening and closing device for 15 box cars comprising a door clamp adapted for attachment to the door, a frame for attachment to the door post at the side of the car, a drum in the frame, a handle for turning said drum, a pulley in the frame substantially in line with said clamp, a cable for one 20 end attached to the drum to be wound thereon, and connected to said clamp at its other end, and a direction changing element carried by the cable adapted for connection to the side 25 of the box car for changing the direction of movement of the door upon the operation of the drum.

5. A door opening and closing device comprising a clamp for a door having a pair of 30 slidably interconnected jaws, a spring for normally drawing said jaws toward each other to bind against the front and rear edges of the door and each jaw having a coupling element, a frame for attachment to the door 35 post, a drum in the frame, a cable connected at one end of the drum adapted to be wound thereon, a coupling element on the other end of the cable for detachable engagement with the coupling element of the jaw remote from 40 said frame when the device is used for drawing the door into closed position, and a direction changing member carried by the cable for attachment to the side of the box car rearwardly of the door for looping the cable 45 across the door and said side of the car, the coupling element of the cable adapted for detachable engagement with the coupling element of the jaw remote from said direction 50 changing device for drawing the door into 55 open position upon the operation of the drum.

60 In testimony whereof, I have affixed my signature.

SHELIDA P. STARK.
